UNITED STATES PATENT OFFICE.

HARRY S. FOLGER, OF CHICAGO, ILLINOIS, ASSIGNOR TO R. D. SWISHER MANUFACTURING COMPANY, OF CHICAGO, ILLINOIS, A CORPORATION OF ILLINOIS.

SELF-INKING HAND-STAMP.

1,275,893.

Specification of Letters Patent. Patented Aug. 13, 1918.

Application filed March 11, 1915. Serial No. 13,572.

To all whom it may concern:

Be it known that I, HARRY S. FOLGER, a citizen of the United States of America, and a resident of Chicago, county of Cook, and 5 State of Illinois, have invented certain new and useful Improvements in Self-Inking Hand-Stamps, of which the following is a specification.

My invention relates to self-inking hand 10 stamps and has for its object improvements in such stamps.

In the accompanying drawings—

Figure 1 is a front elevation;

Fig. 2 is a side elevation;

15 Fig. 3 is a section on line 3—3 of Fig. 2;

Fig. 4 is a section on line 4—4 of Fig. 3; and

20 Fig. 5 is a plan of the blank used in forming an interior frame or casing which will here be called a box.

The frame of the stamp, which has been called an outer frame in self inking stamps of a similar character, consists of side plates 10 and 11 connected together below by tie 25 bolts 12. These side plates are formed of sheet metal and have long vertical slots 13 which extend from the upper ends of the plates to near the bottom. So made the plates 10 and 11 are nearly cut in two by 30 the open upper ends of the slots. The slots are made long so as to give long guides for the movement hereinafter to be described, and they are left open at the top because, to extend the metal of the side plates upward 35 to close the upper ends of the slots, would make the side plates strike the operator's hand when operating the stamp unless the handle were made inconveniently long.

The weakness of the plates 10 and 11 40 caused by cutting slots 13 is partly overcome by turning outward the flanges 14, which flanges are formed from part of the metal removed to form the slot. These flanges serve to prevent lateral bending of the upper 45 parts of the side plates. The parts of the side plates below the slots 13 are also stiffened by beads 15 pressed into the metal as shown, one end of one of these beads being made to serve an additional purpose to be 50 described.

A box 16 is formed from a piece of metal shown in Fig. 5, and bent along the dotted lines. The rectangular parts of this piece form the top, front and back of the box, while

the ends are formed by the wings 17. After 55 being bent to position the joints are secured by soldering or brazing. A short straight piece of metal 18 has its ends bent into hooks 19 (Fig. 3), and this piece is then inserted into the lower open end of the box 16 and 60 soldered in place. As so constructed the edges of the box and the piece 18 form a channel for holding the removable type 20.

Extending through and supported in the box 16 are shafts 21, which shafts extend 65 through the slots 13 and carry guide blocks 22 on their ends. These guide blocks or slides are in the form of channels which embrace and are guided by the flanges 14 on the side plates. As so arranged the shafts 70 21 act as tie rods between the upper parts of the side plates 10 and 11, and the channel form of the guide blocks 22 causes these blocks to act as ties across the upper ends of the slots 13. 75

On a shaft or rod 23 is pivoted a swinging frame 24 which carries a removable ink pad 25 adapted to engage the face of the type 20. Links 26 between the lower shaft 21 and the frame 24 serve to connect the box 16 and 80 pad frame 24 so that they move together. A spring 27 (Fig. 4) on the shaft 23 serves to elevate the box 16 and draw or force the pad 25 against the type 20. Pressure applied by hand to the handle 28 moves the 85 pad rearward and the stamp downward to printing position.

Pivoted at 29 (Fig. 2) is a catch 30 adapted to engage notches 31 in the adjacent guide block or slide 22 to hold the stamp in a depressed position against the action of spring 27. The catch 30 has a projection 32 adapted to engage the end of the adjacent bead 15 to limit the outward movement of said catch. This outer position is shown in Fig. 2 and 90 is such that the upper end of the catch projects slightly beyond the edge of the plate 10 to which it is pivoted. The inner position of the catch is one in which the upper outer edge of said catch substantially matches the 95 edge of the plate 10. As so constructed the catch 30 is made to engage one of the notches 31, when the stamp is depressed, by simply pushing the thumb or finger along the edge of the plate 10. 100

At one end of the plate out of which the box 16 is formed are certain lugs 33 which are conveniently formed by punching them 105

from the metal of the plate. These are arranged so as to form a holder for the card 34 located on the front face of the box 16.

The box 16 is shown tapered. It may, 5 however, be of any form. Its function is to provide a type holding channel below and serve as a handle support above. Also, to furnish connections between the stamp and the guide blocks. By making the connection 10 between the type channel and the handle of the box form, the self inker is given a neat appearance. By making the box, the type channel and the card holder from a single piece of sheet metal there are economy 15 and convenience in construction. The box form gives lightness and provides height which prevents the hand from striking the frame when the stamp is depressed. The lowest position of the top of the box is preferably on a level with the tops of the side 20 plates 10 and 11.

What I claim is:—

1. In a hand stamp, a box formed of sheet metal, said box being closed above and on its 25 four sides by the metal from which the box is formed and providing a narrow opening below, and a bridge inserted in the opening and secured to the box, the front and rear sides of the box at the opening serving as 30 the sides of a type holding channel, and the bridge serving as the bottom of such channel.
2. In a self inking hand stamp, a box providing a type holding channel below and a 35 handle connection above, said box being formed from a single piece of sheet metal bent to inclose all faces of said box except that providing the type holding channel, and a bottom to said channel, said bottom being 40 formed by a strip of metal inserted in the open face of said box and secured to the edges thereof.
3. In a hand stamp, a box formed of sheet

metal bent to close the top and front and rear faces of the stamp and arranged to provide a narrow opening below, and a bridge inserted in said opening and secured to the box, the front and rear faces of the box at the opening serving as the sides of a type holding channel, and the bridge serving as 50 the bottom and ends of such channel.

4. In a self inking hand stamp, a frame having two sections consisting of sheet metal plates having open ended slots in the upper end of said plates, said slots being bounded 55 on their sides by reinforcing flanges bent from the plates and having reinforcing beads extending below and around the lower ends of the slots to stiffen the plates at these places, a reciprocating stamp in the frame, 60 slides secured to the stamp and operating upon the flanges as guides to guide the stamp in the frame, and a catch pivoted to one plate and adapted to engage a notch in the adjacent slide to hold the stamp at a 65 fixed position in the frame, said catch being arranged to engage the adjacent bead to limit the outward movement of the catch, substantially as described.

5. In a self inking hand stamp, a frame 70 consisting of side plates connected together by tie rods, said plates having vertical slots therein open at their upper ends and said plates being reinforced at the edges of the slots by flanges bent from the plates to form 75 the slots, a stamp located between the side plates and slides secured to said stamp and arranged to embrace said flanges so as to form ties for the open upper ends of said slots.

Signed at Chicago, Ill., this 9th day of March, 1915.

HARRY S. FOLGER.
